UNITED STATES PATENT OFFICE.

OSCAR BENJAMIN CRITCHLOW, OF LEADVILLE, COLORADO, ASSIGNOR OF ONE-HALF TO JOHN B. FITZPATRICK, OF SAME PLACE, AND LUCIEN P. CURTIS, OF DENVER, COLORADO.

CONVERTIBLE FREIGHT-CAR.

SPECIFICATION forming part of Letters Patent No. 669,876, dated March 12, 1901.

Application filed June 19, 1900. Serial No. 20,826. (No model.)

To all whom it may concern:

Be it known that I, OSCAR BENJAMIN CRITCHLOW, a citizen of the United States, and a resident of Leadville, in the county of 5 Lake and State of Colorado, have invented a new and Improved Convertible Freight-Car, of which the following is a full, clear, and exact description.

The object of the invention is to provide a 10 new and improved convertible freight-car which is simple and durable in construction and arranged to permit of conveniently converting it from an ordinary flat-bottom box-car used for carrying freight to a hopper-bottom box-car for carrying grain and the 15 like.

The invention consists of novel features and parts and combinations of the same, as will be fully described hereinafter and then 20 pointed out in the claims.

A practical embodiment of the invention is represented in the accompanying drawings, forming a part of this specification, in which similar characters of reference indicate corresponding parts in all the views.

Figure 1 is a side elevation of the improvement with parts broken out. Fig. 2 is a sectional plan view of the same with parts broken out and parts removed. Fig. 3 is an 30 enlarged transverse section of the improvement arranged as a hopper-bottom box-car. Fig. 4 is an enlarged side elevation of one end of the conveyer-screw. Fig. 5 is an enlarged transverse section of the fastening 35 means for the chamber-door, and Fig. 6 is an enlarged perspective view of one of the sections of the bottom.

The improved car has a box-body A, consisting of floor-timbers A', sides A², ends A³, 40 and a top A⁴, as is plainly illustrated in the drawings, and approximately of ordinary construction. The sides A² of the box-body are provided with suitable doors B for giving access to the interior of said body, and the 45 bottom of the box-body is formed of sections C, adapted to rest either on the floor-timbers A' to form the bottom for an ordinary flat-bottom box-car, as indicated in dotted lines in Fig. 3, or the said sections C may be ar- 50 ranged in an inclined position extending from

the sides A² of the box-body inwardly and downwardly to within a short distance of the middle of the car to form a hopper-bottom box-car, as indicated in full lines in Fig. 3. The inner ends of the sections C rest on the 55 central longitudinal beams of the floor-timbers A', while the outer upper ends are formed on their under side with projections C', adapted to hook upon supports D, extending longitudinally on the inner face of the sides A² 60 of the box-body, said supports having removable portions extending across the door-openings for the doors B.

Each section C is provided on top with a suitable ring C², adapted to be taken hold of 65 by the operator to conveniently place the bottom-sections in either the inclined or the horizontal position above referred to, and over the joint of the upper ends of the sections with the sides of the car extends a longitudinal strip of canvas C³, preferably fastened to the sides of the car to prevent grain or like loose material from lodging between the sides of the car and the upper ends of the sections C.

The space between the central longitudinal 70 beams of the floor-timbers A' and into which discharge the lower ends of the bottom-sections C when in an inclined position forms a conveyer-casing E, in which extends a conveyer-screw F, journaled in suitable bearings 75 carried by the floor-timbers A'. The casing E is connected with a suitable discharge-spout G, located either at the middle or one at each end of the car-body, so that when the conveyer-screw is rotated the grain is 80 moved in the casing E to the said spout or spouts for discharging the grain from the 85 box-body.

Each outer end of the shaft of the conveyer-screw F is tapped to receive the threaded end 90 of the shaft F' of a pulley F², adapted to be connected by belt with other machinery for imparting a rotary motion to the conveyer-screw for moving the grain to the spouts G, as above described. The shaft F' is pro- 95 vided with a pin F³, adapted to abut against a lug F⁴ on the conveyer-screw shaft to prevent the pulley-shaft F' from screwing too far into the conveyer-screw shaft.

When the grain is stored in the box-body 100

A and the car is in transit, then the entrance to the space is closed by suitable slides H, mounted to slide transversely in suitable bearings in the floor-timbers A', and each 5 slide H carries at its outer end a nut H', screwing on a screw-rod I, mounted to turn in suitable bearings in the floor-timbers A', a hand-wheel I' being on the outer end of the screw-rod, as is plainly shown in Fig. 3. 10 The hand-wheel I' extends in a chamber A⁵, formed in the floor-timbers A', and the outer side of said chamber consists of a door A⁶, hinged at A⁷ to the floor-timbers near the side A² of the car. The door A⁶ is normally 15 locked—that is, during the time the car is in transit—and for this purpose the inner side of the door is provided with keepers J, engaged by catches J', secured on a shaft J², extending longitudinally in the chamber A⁵ 20 and journaled in suitable bearings carried by the floor-timbers A'. On one outer end of the shaft J² is secured a handle J³, adapted to be locked by a suitable lock or seal to the end of the car-body, so that unauthorized 25 persons cannot turn the shaft J² without detection, and consequently the chamber A⁵ under normal conditions is closed and no access is had to the hand-wheel I'.

When it is desired to unload the car of its 30 grain, then an authorized person unlocks the handle J³, so as to turn the shaft J² and move the catches J' out of engagement with the keepers J. The doors A⁶ are now swung open to give access to the hand-wheels I', 35 which are now turned by the operator to turn the screws I and move the several slides H outward. When this takes place, the grain in the car-body passes into the casing E and is moved by the now-rotated conveyer-screw 40 F to the discharge spout or spouts G, as previously explained.

In order to properly ventilate the car, suitable doors K are arranged in the sides of the car A², near the upper ends thereof, and said 45 doors are connected at their lower ends by hinges K' with the sides of said car and are held in either an open or closed position by links K², pivoted to the sides of the said doors K. The doors K also form a hopper through 50 which the car may be filled with grain.

In order to prevent the grain from falling through cracks between adjacent sections, I prefer to so form the sections that they will overlap at their sides, as indicated in Fig. 6. 55 It is understood that when the car is in transit the pulley F² is removed from the conveyer-screw and is stored, preferably, in the chamber A⁵, so that the conveyer-screw cannot be accidentally turned during the time 60 the car is in transit.

Having thus fully described my invention, I claim as new and desire to secure by Letters Patent—

1. A convertible freight-car, comprising a 65 box-body having longitudinal supports, and a floor for the body and adapted to be hung on said supports and extend in an inclined direc-

tion from the sides of the car-body to near the longitudinal middle thereof, the inner ends of the floor resting on the longitudinal beams of 70 the floor-timbers of the car, substantially as shown and described.

2. A convertible freight-car, comprising a box-body having supports extending longitudinally on the inner face of the sides of the 75 box-body, and a floor for the body made in sections and arranged to either extend in a horizontal position on the floor-supporting timbers, or hang with their outer ends on said longitudinal support and extend in an inclined direction from the sides of the car-body, with the inner ends of the floor-sections resting on the central longitudinal beams of 80 the floor-timbers, as set forth.

3. A convertible freight-car, comprising a 85 box-body, having supports extending longitudinally on the inner face of the sides of the box-body, a floor for the body and made in sections having projections on their outer 90 ends at the under side, the sections being arranged to either extend in a horizontal position on the floor-supporting timbers or hang with their outer projecting ends on said supports, and extend from the sides of the car-body inward and downward in an inclined 95 direction to the floor-timbers, with the inner ends of the floor-sections resting on the central longitudinal beams of the floor-timbers, the space between the said central longitudinal beams forming a conveyer-casing, into 100 which discharge the lower ends of the floor-sections when in an inclined position, and a conveyer-screw extending longitudinally in said casing, as set forth.

4. A convertible freight-car, comprising a 105 box-body having longitudinal supports, a floor for the body and made in sections arranged to either extend in a horizontal position on the floor-supporting timbers, or hang with their outer ends on said supports and extend from 110 the sides of the car-body inward and downward in an inclined direction to the floor-timbers at or near the middle of the car, a conveyer-casing having a conveyer-screw at the 115 middle of the car and into which discharge 120 said floor-sections, and slides for closing said casing and manually controlled from the outside of the car, as set forth.

5. A convertible freight-car, comprising a 120 box-body having longitudinal supports, a floor for the body and adapted to be hung on said supports and extend in an inclined direction from the sides of the car-body to near the middle thereof, and a strip of flexible material secured to the sides of the car and extending 125 over the joint between the floor-sections and the sides of the car-body, as set forth.

6. A freight-car having a box-body provided on the inner face of its sides with longitudinally-extending supports, movable inclined 130 floor-sections having projections on their under sides at their outer upper ends adapted to hook upon the said supports, a conveyer-casing extending longitudinally in the bot-

tom of the car and into which discharge said floor-sections, a conveyer-screw in said conveyer-casing, and a discharge leading from the said casing, substantially as shown and described.

5 7. A freight-car having a box-body with movable inclined floor-sections, a conveyer-casing in the bottom of the car and into which discharge said floor-sections, a conveyer-screw in said conveyer-casing, a discharge leading from said casing, and slides for closing said casing at the top thereof, as set forth.

10 8. A freight-car having a box-body with movable inclined floor-sections, a conveyer-casing in the bottom of the car and into which discharge said floor-sections, a conveyer-screw in said conveyer-casing, a discharge leading from said casing, slides for closing said casing at the top thereof, each slide having a 15 nut, a screw-rod mounted to turn and engaged by said nut, and a hand-wheel for said screw-rod and extending in a normally closed and locked chamber on said car-body, as set forth.

20 9. A freight-car having a box-body with movable inclined floor-sections, a conveyer-casing in the bottom of the car and into which discharge said floor-sections, a conveyer-screw in said conveyer-casing, a discharge leading from said casing, slides for closing said casing at the top thereof, each slide having a nut, a screw-rod mounted to turn and engaged by 25 said nut, a hand-wheel for said screw-rod the said hand-wheel being located in a normally closed and locked chamber on the car-body, said chamber having a hinged door, and means for locking said door, as set forth.

30 10. A freight-car having a conveyer-screw, and a removable pulley for the same, said

pulley having a shaft provided with a threaded end adapted to screw in the tapped end of the shaft of the conveyer-screw, the shaft of the pulley being provided with a pin adapted to abut against a lug on the conveyer-screw shaft for the purpose set forth.

45

11. A freight-car, comprising a box-body having supports extending longitudinally on the inner face of the sides of the box-body, the said supports having removable portions extending across the openings for the doors in the sides of the cars, movable inclined floor-sections engaging with their outer ends the said supports, a conveyer-casing in the bottom of the car and into which discharge said floor-sections, and slides for closing said casing at the top thereof, as set forth.

50

12. A freight-car having a box-body with movable inclined floor-sections, a conveyer-casing in the bottom of the car and into which discharge said floor-sections, a conveyer-screw in said conveyer-casing, a discharge leading from said casing, slides for closing said casing at the top thereof, means for moving the slides, the said means extending within a chamber on the car-body, a hinged door for 60 said chamber provided on the inner side with keepers and a shaft extending longitudinally in the chamber and mounted to turn, the said shaft being provided with catches adapted to engage the keepers on the door, as set forth.

65

In testimony whereof I have signed my name to this specification in the presence of two subscribing witnesses.
